RAILWAY SIGNALING APPARATUS

Henry S. Young, Wilkinsburg, Pa., assignor to
The Union Switch & Signal Company, Swiss-
vale, Pa., a corporation of Pennsylvania

Application October 20, 1941, Serial No. 415,744

3 Claims. (Cl. 246—219)

My invention relates to railway signaling apparatus, and it has particular reference to the organization of such apparatus into novel and improved railway signaling systems of the class wherein a signal is caused at times to be steadily energized to provide one indication, and at other times to be intermittently energized or flashed to provide a distinctively different indication.

Railway signaling systems of the above described class have been proposed heretofore for use in controlling diverging route and call-on movements over a switch. Ordinarily, both call-on and diverging route movements are authorized by the same indication, usually by a caution aspect displayed by the lower unit or arm of a signal governing traffic over a switch. It has, however, been considered desirable to provide distinctively different indications to authorize call-on and diverging route movements respectively, thereby to inform trainmen of the proposed route and to avoid the possibility that trainmen might accept a caution indication at a switch in the belief that a diverging route movement is authorized whereas in fact the indication might relate to a call-on move. Accordingly, it has been proposed to cause a signal to display a steady caution aspect when a diverging route move is authorized, and to display a flashing caution aspect when a call-on move is authorized.

In such systems, it is essential that means be provided to insure against a failure of the apparatus causing a signal to display a steady caution indication when a flashing indication should be displayed. It is, therefore, an object of my invention to provide signal systems of the class described and incorporating novel and improved means for checking the flashing indication of a signal to prevent a false steady illumination of such signal.

Another object is to provide novel and improved signal systems of the class described.

The above-mentioned and other important objects and characteristic features which will become readily apparent from the following description, are attained in accordance with my invention by utilizing contact operating means for flashing the signal, and a checking relay to detect operation of the contact operating means. When the apparatus is conditioned to display a flashing indication, the checking relay is first fully energized. After the checking relay is picked up, energy is applied to the contact operating means to cause such means to operate and intermittently energize the signal, and also to intermittently interrupt the energization of the

checking relay during each lighted interval of the signal.

I shall describe two forms of apparatus embodying my invention, and shall then point out the novel features thereof in claims.

In the accompanying drawing, Fig. 1 is a diagrammatic view illustrating one form of apparatus embodying my invention. Fig. 2 is a diagrammatic view representing a modified form of the apparatus shown in Fig. 1, and also embodying my invention. In each of the two views, similar reference characters have been employed to designate corresponding parts.

Referring to Fig. 1 of the drawing, the reference character T designates a section of railway track including a track switch W, and provided in the usual manner with a normally closed circuit track circuit which includes a track relay TR, as indicated conventionally in the drawing. Switch W has associated therewith a switch repeater relay WPR controlled by the position of switch W through the medium of circuit controlling contacts 5 and 6 operatively associated therewith, the arrangement being such that when switch W is in its normal position, as represented in the drawing, contacts 5 and 6 engage fixed contacts 7 and 8, respectively, and relay WPR is energized over an obvious circuit by current of one relative polarity to cause its front contact 10 and its normal polar contact 11—12 to be closed. When switch W is in its reverse position, contacts 5 and 6 engage fixed contacts 8 and 9, respectively, to reverse the polarity of current energizing relay WPR, as can readily be seen from an inspection of the drawing, and relay WPR is caused to shift its polar contact member 11 and close its reverse polar contact 11—13.

Section T has associated therewith a signal 2 for governing traffic movements over switch W. Signal 2 comprises two arms or signal units a and c, which units may comprise any suitable type of signal, such as color light, position light, etc., but for the purposes of the present description it will be assumed that the units are of the search-light signal type comprising a rotor 15 operated by a winding 16 and having associated therewith colored roundels, r, g and/or y, one or the other of which roundels is moved into the path of a beam of light projected from an associated lamp 17. Each unit is arranged so that when its associated winding 16 is deenergized, a red roundel r is interposed in the path of the beam of light projected from its associated lamp, and the unit accordingly is caused to display a red aspect. When winding 16 of unit 2a is energized,

a green roundel *g* is caused to move into the path of light from the associated lamp *17* and unit *2a* accordingly is caused to display a green aspect. When winding *16* of unit *2c* is energized, a yellow roundel *y* is interposed in the path of light projected from its lamp *17* and as a result unit *2c* is caused to display a yellow aspect.

The reference characters *V* with suitably distinguishing prefixes designate manually operable control levers which may, for example, be levers of an interlocking machine positioned in a control or interlocking tower. Each lever normally occupies a normal position *N*, as indicated in the drawing, and is operable to a reverse position *R*. Operatively associated with each lever are circuit controller contacts which are selectively closed in accordance with the position of the associated lever, and each of such contacts bears a reference character *N* or *R* to indicate the position of its associated lever in which such contact is closed. For example, contact *20* of lever *2V* bears a reference character *R* to indicate that such contact is closed when lever *2V* is in its reverse position *R*, while contact *21* of lever *1V* bears a reference character *N* to indicate that contact *21* is closed when its associated lever is in its normal position *N*.

Signal *2* is controlled in the usual manner by levers *V*, the position of switch *W*, and traffic conditions in section *T*. Both units are normally deenergized and hence are caused to display their respective red aspects, but when section *T* is unoccupied and switch *W* is in its normal position, unit *2a* may be caused to display its green aspect by the operator reversing lever *2V* to complete a circuit which may be traced from one terminal *B* of a suitable source of current, such as a battery not shown but having its opposite terminals designated by the reference characters *B* and *C*, through contact *20* of lever *2V*, front contact *10* and normal polar contact *11-12* of relay *WPR*, contact *21* of lever *1V*, front contact *22* of relay *TR* and winding *16* of unit *2a* to terminal *C*. Roundel *g* of unit *2a* accordingly is interposed in the path of light projected from lamp *17*, which lamp is steadily energized over an obvious circuit. When switch *W* is in its reverse position, lever *1V* is in its reverse position *R*, and section *T* is unoccupied, unit *2c* may be caused to display a steady yellow aspect by the operator reversing lever *2V* to complete a circuit extending from terminal *B* through contact *20* of lever *2V*, front contact *10* and reverse polar contact *11-13* of relay *WPR*, contact *23* of lever *1V*, front contact *24* of relay *TR*, back contact *25* of a relay *COR*, to be referred to hereinafter, and winding *16* of unit *2c* to terminal *C*. Roundel *y* of unit *2c* accordingly is interposed in the path of light from its associated lamp, which lamp is at this time steadily energized over an obvious circuit including back contact *26* of relay *COR*.

A call-on or checking relay, designated by the reference character *COR*, and suitable contact operating means provided with circuit controlling contacts which are periodically opened and closed, are also provided and cooperate to cause unit *2c* at times to display a flashing yellow aspect. The contact operating means, as here shown, comprises a flasher relay *FR* having two windings *28* and *29* for reversibly operating an armature *30* which is biased, as by a weight *31*, to assume one extreme position when windings *28* and *29* are deenergized. Operatively associated with armature *30* are a plurality of circuit con-

trolling contact members which engage fixed contact members in one position or the other of armature *30*. When armature *30* of relay *FR* is in its biased one extreme position, contact member *32* engages member *33*, and contact member *36* engages member *37* to provide an obvious shunt path around winding *29* so that when energy is applied to relay *FR*, winding *28* is energized to cause armature *30* to operate to its other extreme position wherein contact member *34* engages contact *35*, and contact member *36* engages contact *38* to complete an obvious shunt path around winding *28*, whereupon winding *29* becomes energized to attract armature *30* and cause it to operate back to its one extreme position. The parts of relay *FR* are proportioned in such manner that when energy is applied to its windings, armature *30* is caused to operate between its two extreme positions at a rate of, say, 30 times a minute.

Relay *FR* is energized only after relay *COR* is energized to close its front contact *40* and thereby complete an obvious circuit including a source of current, front contact *40* of relay *COR* and the windings of relay *FR*. Relay *COR* is energized over a circuit which includes contact *32-33* of relay *FR*, closed in the one or biased extreme position of the armature of relay *FR*, and which circuit extends from terminal *B* through contact *20* of lever *2V*, front contact *10* and normal polar contact *11-12* of relay *WPR*, contact *41* of lever *1V*, contact *42* of call-on push button *COPB*, contact *33-32* of relay *FR* and the winding of relay *COR* to terminal *C*. Relay *COR* accordingly must be picked up over its previously traced circuit prior to energy being applied to relay *FR* to cause it to operate and intermittently open and close its contact *32-33* to intermittently deenergize relay *COR*. Relay *COR* is provided with slow release characteristics selected to maintain the relay energized during the intervals that contact *32-33* of relay *FR* is open, hence once relay *COR* is picked up while relay *FR* is not operating, relay *COR* is maintained picked up due to energy intermittently supplied to its windings during the intervals that contact *32-33* of relay *FR* is closed.

When switch *W* and lever *1V* are in their respective reverse positions, an alternate path is provided in the just traced circuit of relay *COR*, which path extends from front contact *10* through reverse polar contact *11-13* of relay *WPR* and contact *43* of lever *1V* to contact *42* of push button *COPB*.

Push button *COPB*, as represented in the drawing, is of the stick type arranged to remain in its last operated position, hence when contact *42* of push button *COPB* is closed, it remains closed to condition relay *COR* to be energized over its previously traced circuit as long as lever *2V* is in its reverse position. If, however, a non-stick type of push button is utilized, as indicated in Fig. 2, then relay *COR* may be provided with a stick circuit, shown in Fig. 2, which circuit includes its own front contact *44* connected around contact *42* of push button *COPB-1* and which stick circuit conditions relay *COR* to be energized as long as lever *2V* is in its reverse position. It follows that although contact *42* of push button *COPB-1* may be released to open the previously traced pick-up circuit of relay *COR* in Fig. 2, such relay remains energized over its stick circuit path until such path is interrupted at contact *20* of lever *2V*.

Relay *COR*, when energized, closes its front

contact 25 to complete an obvious circuit for winding 16 of unit 2c, whereupon that unit is caused to position its yellow roundel y in the path of light projected from the associated lamp 17. When relay COR is energized, relay FR is of course caused to operate and lamp 17 of unit 2c is intermittently energized at this time over a circuit extending from terminal B through contact 34-35 (when closed) of relay FR, front contact 26 of relay COR and the filament of lamp 17 to terminal C. It is thus apparent that when an operator actuates push button COPB to authorize a closing-in or call-on movement, the apparatus provides a flashing caution indication which is distinctively different from the steady caution indication caused to be displayed when a diverging route movement is authorized. In the event that the apparatus fails to operate properly when a flashing indication should be displayed, the arrangement is such as to prevent a steady caution aspect. For example, should relay FR fail to operate properly and stop with its contact 32-33 closed, relay COR is energized, but lamp 17 of unit 2c is deenergized and hence the unit exhibits a dark indication. On the other hand, if the relay stops with contact 34-35 closed, then relay COR is deenergized and drops at the end of its slow release interval to interrupt, at its front contact 25, a previously traced circuit of winding 16 of unit 2c, whereupon roundel r is interposed in the path of light from lamp 17, which lamp is now steadily energized over back contact 26 of relay COR. It follows, therefore, that when the apparatus fails to operate properly to provide a flashing caution indication, unit 2c is then caused to display either a dark aspect or a lighted red aspect, either of which aspects under the rules of operation requires a train approaching the signal to be brought to a stop.

An advantage of the checking apparatus involving relay COR and embodying my invention is that the relay is fully energized and picked up prior to applying energy to the flashing relay FR, and relay COR is intermittently energized only after it once picks up to cause relay FR to operate. This arrangement permits the pick-up energy level in relay COR to be built up without interruption due to operation of relay FR, and after relay FR starts operation, enables relay COR to be held up by impulses of energy supplied when contact 32-33 of relay FR is closed and having a value selected so as to

maintain the energy level in the relay above its release level.

Although I have herein shown and described only two forms of railway signaling apparatus embodying my invention, it is understood that various changes and modifications may be made therein within the scope of the appended claims without departing from the spirit and scope of my invention.

Having thus described my invention, what I claim is:

1. In a railway signal system of the class wherein a signal at times is steadily energized for providing one indication and is intermittently energized for providing a distinctively different indication, the combination with a signal, a checking relay, and a normally quiescent flasher relay of the type having its armature biased to one of its two extreme positions, of an energizing circuit for said checking relay completed through a contact of said flasher relay closed in the biased position of said armature, an energizing circuit for said flasher relay completed through a front contact of said checking relay, and a circuit for said signal including a contact of said flasher relay closed in the other of its said two extreme positions.

2. In a railway signal system of the class wherein a signal at times is steadily energized for providing one indication and is intermittently energized for providing a distinctively different indication, the combination with a signal, a checking relay, and a normally inactive contact operating means having contacts closed in one or another of two different positions and biased to cause contacts in a given position to be closed when said means is inactive, of an energizing circuit for said checking relay including a contact of said contact operating means closed in its said one biased position, an energizing circuit for causing operation of said contact operating means and including a contact of said checking relay closed when said checking relay is energized, and a circuit for said signal including a contact of said contact operating means closed in the other position of said means.

3. A railway signal system according to claim 2, characterized by the fact that the circuit for the signal also includes a contact of said checking relay closed when said checking relay is energized.

HENRY S. YOUNG.
